UNITED STATES PATENT OFFICE.

WILLIAM M. RAPP, OF WESTMONT, NEW JERSEY.

LINOTYPE-MACHINE.

1,101,660.

Specification of Letters Patent. Patented June 30, 1914.

Application filed December 9, 1913. Serial No. 805,516.

To all whom it may concern:

Be it known that I, WILLIAM M. RAPP, a citizen of the United States, residing at Westmont, in the county of Camden and State of New Jersey, have invented certain new and useful Improvements in Linotype-Machines, of which the following is a specification.

My invention relates to improvements in linotype machines; the object of the invention is to provide an improved construction of assembler slide, carrying one scale of a vernier gage registering with an adjustable fixed scale, whereby accurate measurements of the assembled line are always apparent from a glance at the registering scales.

A further object is to provide an improved construction of brake for the assembler slide.

With these and other objects in view, the invention consists in certain novel features of construction and combinations and arrangements of parts as will be more fully hereinafter described and pointed out in the claims.

In the accompanying drawings: Figure 1 is a view in front elevation illustrating the assembling mechanism of an ordinary linotype machine with my improvements in operative position. Fig. 2 is a top plan view of my improvements detached. Fig. 3 is a view in section on the line 3—3 of Fig. 1. Fig. 4 is a view in section on the line 4—4 of Fig. 1. Fig. 5 is a view in section on the line 5—5 of Fig. 1. Fig. 6 is a view in section on the line 6—6 of Fig. 1. Fig. 7 is a view in section on the line 7—7 of Fig. 1. Fig. 8 is a perspective view of my improved brake shoe, and Fig. 9 is a view in section on the line 9—9 of Fig. 1.

1 represents a portion of the frame of an ordinary linotype machine, 2 the elevator, and 3 the star wheel which are common to machines of this type. While I have illustrated my invention in connection with such a machine, I would have it understood that my improvements are equally well adapted for use in connection with an intertype or slug casting or typesetting machine, and hence I do not limit myself to the particular use.

4 represents my improved assembler slide

which comprises a channel bar movable through guides 5 and 6, said guides integral with a plate 7, and said plate adapted to be secured to the machine. One end of this slide 4 is connected by the ordinary link 8 with the ordinary spring 9 for returning the slide to normal position with its finger 10 against the star wheel 3. It will be noted that the finger 10 is rigidly secured to the slide 4 by screws 11, so that there can be no movement whatever of the finger relative to the slide.

An angular collar 12 having spacing blocks 12^a therein, is adjustably secured to the slide 4 by means of a set screw 13, and this collar 12 engages the rear guide 6 to limit the movement of the assembler slide and regulate the length of the line of matrices set up. The set screw 13 permits the line to be adjusted at will by moving the collar to any position on the slide.

On the side of the collar 12, a perforated lug 12^b is provided to receive a wire 12^d held by a screw 12^c. The wire may be inserted to blank off the scale where the operator wishes to line up, so that the length of line is always apparent.

A scale plate 14 is fixed to the assembler slide 4 and registers with a scale plate 15 secured to an angle bar 16. The lower member of the angle bar 16 is provided with a longitudinal slot 17 through which a screw 18 projects, said screw engaging in a threaded opening in an integral lug 19 on plate 7, and by this arrangement of parts, the scale 15 may be adjusted longitudinally. The scales 14 and 15 constitute a vernier gage, the former indicating in points, and the latter in picas, and by their combination indicating at all times the precise length of the line of matrices set up. By this arrangement of parts, the finger 10 may be rigidly fixed to the assembler slide 4 as above described, and yet allow of an accurate adjustment of parts to insure a perfect measurement even after the parts become worn, because in order to secure an accurate arrangement of the scale, it is simply necessary to move the slide to bring the finger 10 against the star wheel, and then adjust the scale 15 as above described to bring the scales to zero.

It will be noted by reference to Fig. 1

that the spaces of the lower fixed scale 15 are appreciably smaller than the spaces of the movable scale on the slide. To be more accurate, the scale 15 is divided into twelve 5 equal parts, and the divisions of the scale 14 are each one-twelfth longer than the divisions of the scale 15.

The lower guide lug 6 is provided with an 10 integral forwardly projecting tongue 20 having a set screw 20^a therein adapted to clamp an ordinary slug 20^b such as commonly made in linotype machines. This slug 20^b will be positioned as shown in Fig. 1 when it is 15 desired to do ditto work, so that the operator can keep before him the proper slug to place ditto marks in the line as will be readily understood.

In connection with my improved assembler slide, I provide an improved construction of brake comprising a lever 21 which is 20 fulcrumed between its ends on the reduced inner end 22 of a turn button 23. One end 24 of this lever 21 is adapted to be operated by the elevator to release the assembler slide 25 when the line of matrices is elevated, as is customary in machines of this character, while the other end of said lever is movable between lugs 25 and 26 projecting inwardly from an arm 27 which latter is also fulcrumed between its ends on the reduced 30 inner end 22 of turn button 23.

The end of lever 21 is appreciably narrower than the space between lugs 25 and 26 to allow of a pre-determined movement 35 of the lever, and this movement is regulated by a screw 28 screwed through lug 26 and locked against accidental movement by a jam nut 29. One end of the arm 27 is formed on its inner face with an angular 40 recess 30 to receive a tongue 31 integral with a plate 32 on which a strip 33, preferably of raw hide, is secured by screws 34. This plate 32, tongue 31, and strip of raw hide 33 constitute what I shall term a "brake 45 shoe," because the strip 33 is positioned within the channel bar assembler slide 4, and exerts frictional contact therewith when the lever is in the position indicated.

A spring 35 is coiled at one end around 50 the turn button 23 and projected through an opening 36 in the head of said turn button, while the opposite end of the spring exerts upward pressure on a lug 37 integral with arm 27.

55 A screw 38 extends through the central bore of the turn button 23, and is screwed into plate 7, the head of said screw 38 being countersunk in the turn button. By releasing this screw 38, the turn button may be 60 revolved to adjust the tension of the spring, and when the proper adjustment is had, the screw is screwed home to clamp the turn button against movement. The tension of the spring tends to move the arm 27 and 65 the lever 21 in a direction to position the

strip 33 at a slight angle to the assembler slide 4. In other words, the tendency of the spring is to move the strip 33 out of parallelism with the slide 4, so that a strong frictional gripping action is had against the parallel members of the channel bar constituting the slide, holding the slide against any tendency of the spring 9 to return the same. Furthermore, this construction of brake allows the slide to be manually operated at any time to move the slide in either direction and allow a wide range of manipulation with reference to the matrices and to the other parts of the apparatus without releasing the brake.

The particular connection between the end of lever 21 and the arm 27 allows a predetermined amount of independent movement of the lever before the brake is operated, this movement being regulated by the 85 screw 28. Such an arrangement prevents any possibility of the brake being released by vibration of the parts, and also permits of a nice adjustment between the lever and the elevator to properly time the release 90 of the assembler slide when the matrices are moved by the elevator.

In operation, as the matrices, indicated at 40, are pressed against the finger 10 by the star wheel 3, the assembler slide is moved 95 against the action of spring 9. As the scale 14 is fixed to the slide 4, its indicating marks will register with the marks of the fixed scale 15, so that a glance at the scales will indicate at any and all times the exact length 100 of the line of matrices set up, and also allow of a wide range of manipulation of the slide to take out matrices, or place spacers, or correct mistakes, without releasing the slide. In other words, not only does the 105 scale accurately indicate to the operator just the measurement of the line, but permits the manipulation of the slide to correct mistakes in the setting up of the matrices, and also enables the slide to be moved in either 110 direction and held in any position of adjustment by reason of the particular brake. The slide can be easily released by operating the lever 21 when the spring 9 will return the slide to normal position. By adjusting the 115 tension of the spring 25, the frictional engagement of the brake shoe is adjusted. This is important because in the course of time it becomes necessary to change the tension to secure the proper frictional engagement.

My improvements are so constructed and arranged that they may be readily attached to any ordinary machine in use, and will operate with equal efficiency upon old machines as well as new ones.

Various slight changes might be made in the general form and arrangement of parts described without departing from my invention, and hence I do not limit myself to 130

the precise details set forth, but consider myself at liberty to make such changes and alterations as fairly fall within the spirit and scope of the appended claims.

5 Having thus described my invention, what I claim as new and desire to secure by Letters Patent is:

1. The combination with a supporting plate having guides thereon, an assembler 10 slide movable in the guides, a member adjustable on the plate and having its outer face flush with the slide, said member and said slide having registering scales on their outer faces, substantially as described.

15 2. The combination with a supporting plate having guides thereon, an assembler slide movable in the guides, an angle bar secured to the plate and having one face flush with the outer face of the slide, said 20 slide and angle bar having registering scales thereon, substantially as described.

25 3. The combination with a supporting plate having guides thereon, an assembler slide movable in the guides, an angle bar secured to the plate and having one face flush with the outer face of the slide, said 30 slide and angle bar having registering scales thereon, and a collar adjustable on the slide and adapted to engage one of said guides to limit the movement of the slide in one direction, substantially as described.

35 4. The combination with a supporting plate, of an angle bar adjustably secured to the supporting plate, guides on the plate, an assembler slide movable in said guides, scale plates secured to the slide and to the angle plate respectively constituting a vernier gage, and a finger rigidly secured to said slide, substantially as described.

40 5. The combination with a supporting plate, of an angle bar adjustably secured to the supporting plate, guides on the plate, an assembler slide movable in said guides, scale plates secured to the slide and to the angle 45 plate respectively constituting a vernier gage, said slide constituting a channel bar, and a brake shoe engaging in the channel bar, substantially as described.

50 6. The combination with a supporting plate, and an assembler slide supported by said plate and having parallel longitudinal flanges, of a lever fulcrumed between its ends on the plate, a brake shoe supported by said lever, said brake shoe having a 55 strip of friction material located between the longitudinal flanges of the slide and covered by the slide, and a spring exerting pressure on said lever and tending to hold the strip of friction material at an angle 60 to the slide, substantially as described.

65 7. The combination with a supporting plate, and an assembler slide supported by said plate and having parallel longitudinal flanges, of a lever fulcrumed between its 65 ends on the plate, a brake shoe supported

by said lever, said brake shoe having a strip of friction material located between the longitudinal flanges of the slide and covered by the slide, a spring exerting pressure on said lever and tending to hold the strip of 70 friction material at an angle to the slide, and means for adjusting the tension of said spring, substantially as described.

8. The combination with a supporting plate, and a channel bar assembler slide 75 supported by said plate, of a lever fulcrumed between its ends on the plate, an arm on the lever having lugs at one end between which one end of the lever is movable, a set screw in one of said lugs limiting 80 the movement of the lever with relation to the arm, a brake shoe carried by the arm and lever and located inside of and covered by the slide, and a spring exerting pressure on the arm tending to move the brake shoe 85 into frictional engagement with the slide, substantially as described.

9. The combination with a supporting plate, and a channel bar assembler slide supported by said plate, of a lever fulcrumed between its ends on the plate, an arm on the lever having lugs at one end 90 between which one end of the lever is movable, a set screw in one of said lugs limiting the movement of the lever with relation 95 to the arm, said arm having a recess therein, a brake shoe having a strip of friction material located within the slide, and a spring bearing against said arm and tending to move the strip of friction material at an 100 angle to the slide, substantially as described.

10. The combination with a supporting plate, and a channel bar assembler slide supported by the plate, of a turn button, a screw affording rotary mounting for said 105 turn button and screwed into the plate, whereby the turn button may be clamped against movement, a lever fulcrumed between its ends on said turn button, an arm fulcrumed between its ends on the turn button and constructed at one end to limit the 110 pivotal movement of the lever with relation to the arm, a brake shoe carried by said arm and lever and engaging the slide, and a spring at one end engaging the arm and 115 at its other end coiled about the turn button and secured thereto, whereby the movement of the turn button adjusts the tension of the spring, substantially as described.

11. The combination with an assembler 120 slide, of a scale on the slide, a second scale secured to a fixed part and registering with a scale on the slide, a collar adjustable on the slide and adapted to engage a fixed part to limit the movement of the slide in one 125 direction, and a wire adjustably connected to the collar and adapted to be positioned in front of the scale on the slide, substantially as described.

12. The combination with an assembler 130

slide, of a scale extending longitudinally of
and fixed to the slide, a second scale secured
to a fixed part and registering with the
scale on the slide, and means for clamping
a slug in proximity to the fixed scale, sub-
stantially as described.

In testimony whereof I have signed my

name to this specification in the presence of
two subscribing witnesses.

WILLIAM M. RAPP.
